APPARATUS FOR COATING ROLLERS

Charles F. Smith, Chicago, Ill., assignor to Rapid Roller Company, Chicago, Ill., a corporation of Illinois

Continuation of application Serial No. 612,747, filed May 21, 1932. This application filed January 13, 1933. Serial No. 651,565

5 Claims. (Cl. 91—43)

This invention relates to an apparatus for coating or resurfacing of printing rolls, as with a coating of a predetermined thickness in accordance with varying requirements.

5 The present application is a continuation of my application entitled "Apparatus for coating printing rolls", Serial No. 612,747, filed May 21, 1932.

10 Coated printer's rollers are constructed with a suitable base, to which is applied a surface coating of the desired thickness having a composition similar to the usual printing roll composition. It has heretofore been proposed to coat or resurface printing rolls by directing against a rotated roll while in an inclined position, a fluid coating composition in an amount substantially in excess of that which will adhere to and remain on the roll, and then to place the coated roll in an upright or endwise position so as to permit endwise draining of the coating composition during the setting or congealing of the composition in place on the roll. Owing to the fact that printing rolls are of varying diameter and may require coatings of varying thicknesses, apparatus heretofore developed for carrying out this method of coating printing rolls has not been entirely satisfactory for the obtaining of the desired thickness of coating on rolls of various diameters.

15 It is therefore an object of this invention to provide an apparatus for and method of coating printing rolls and the like, by means of and according to which printing rolls of varying diameter may be coated with a printing roll composition to the desired thickness uniformly and in a single operation without the necessity of draining any surplus of the coating composition subsequent to the actual coating step.

20 It is a further important object of this invention to provide an apparatus in which printing rolls of varying diameters may be supported for rotation at various angular inclinations depending upon the thickness of the coating desired and wherein the speed of the rotated rolls may be varied in accordance with the diameter of the roll to give substantially the same surface speed for rolls of different diameter, thereby eliminating the variable introduced into the coating operation by varying surface speeds of rolls of different diameters.

25 It is a further important object of this invention to provide an apparatus for coating printing rolls and the like wherein means are provided for disposing a roll to be coated at varying angular inclinations and the roll may be rotated and the stream of coating composition may be moved along the axis of the roll at independently vari-

able speeds, whereby a uniform coating of the desired thickness may be obtained using a single apparatus regardless of the diameter of the printing roll that is to be coated.

30 It is a further important object of this invention to provide an apparatus for coating printing rolls in which provision is made for heating the fluid coating composition to a definite temperature and maintaining that temperature within a narrow range in order to maintain a substantially constant viscosity of the coating composition and thereby eliminate one variable in the obtaining of coatings of the desired thickness and uniformity.

35 It is a further important object of this invention to provide an apparatus for coating printing rolls having means for controlling the rate of flow of coating composition to the roller to be coated and having means for recirculating the surplus of coating composition over that which is retained on the roll.

40 Other and further important objects of this invention will become apparent from the disclosures in the specification and the accompanying drawings.

45 This invention (in a preferred form) is illustrated in the drawings and hereinafter more fully described.

50 On the drawings:

55 Figure 1 is a side elevational view of an apparatus embodying the principles of my invention, with parts broken away and in section.

60 Figure 2 is a broken top plan view of the apparatus shown in Fig. 1.

65 Figure 3 is a fragmentary enlarged sectional view taken substantially on line III—III of Fig. 1.

70 Figure 4 is an enlarged fragmentary sectional view taken substantially on the line IV—IV of Fig. 2.

75 Figure 5 is a fragmentary sectional view taken substantially on line V—V of Fig. 2.

80 Figure 6 is an enlarged fragmentary sectional view taken substantially on the line VI—VI of Fig. 2, with parts in elevation, illustrating the coating operation.

85 As shown on the drawings:

90 The reference numeral 1 indicates as a whole a supporting base for apparatus embodying the principles of my invention for use in the coating of printing rolls and the like. Said supporting base 1 includes a frame structure 2 on which is mounted a jacketed tank 3 for containing a fluid coating composition. A sight glass 4 is associated with the jacket of the tank 3 for indicating the level of the water, or other liquid, within 95

the jacket. The jacket may be filled through a spout 6. A wire mesh or perforated sheet metal basket 5 (Fig. 2) is positioned within the tank 3 at one end thereof so that the fluid coating composition is strained when poured into the tank and before being withdrawn from the tank through a discharge pipe 7 entering the bottom thereof.

At one end of the supporting base 1, a support 10 or standard 8 is mounted from the framework 2. Said standard 8 carries a pair of spaced bearing blocks 9, in which is journaled a transversely extending driven shaft 10 which extends beyond the rear bearing, as at 11, and is provided with a gear 12. Said shaft 10 is also extended at the front side of the machine beyond the bearing 9 and is provided with a sprocket gear 13 fixed thereto. The shaft 10 forms a part of the driving mechanism that will be described hereinafter in greater detail.

An open frame or cradle 14, of generally rectangular shape, is supported from said shaft 10 upon trunnions 15 which freely receive the shaft 10 so as to permit the frame 14 to be pivotally moved about said shaft as an axis regardless of the rotation of said shaft. A quadrant shaped plate 16 is secured to the front trunnion 15 and is graduated to indicate, by means of a pointer 17 secured in a front bearing 9, the angle of inclination of said frame 14.

A longitudinally extending beam 18 is secured at one end to said frame 14 at the rear side thereof and partly supported therefrom. The other end of said beam is supported by a rod 120 which is extensible from a standard 121. Nuts 122 serve to adjust and hold said rod in position to maintain the desired inclination of the beam 18. An auxiliary extensible brace 128 serves to further support the beam 18. Said beam 18 may suitably be of angular cross section, with a vertical web 19 and a right angle flange portion 20. A relatively narrow, elongated guide plate 21 is secured to the top edge of the vertical web 19 for the full length thereof. A trough 22 is supported from the flange 20 and is of such length as to terminate at its lower end 23 directly above the tank 3.

A bracket 24 is slidably mounted upon the guide plate 21 and may be secured in adjusted position therealong by means of a set screw 25. Said bracket 24 is provided with an extension 26 which projects into the trough 22 and carries on its extended end a pair of small rollers 27. Said rollers 27 provide a roller cradle to rotatably support one end of the shaft 28 of a roll 29 to be coated. Movement of the bracket 24 along the guide plate 21 permits the rollers to be positioned at any desired point in accordance with the length of the printing roll 29 that is to be coated.

The frame 14 carries a pair of spaced bearings 30 which are aligned with the bearing provided by the rollers 27. A spindle 31 extends through said bearings 30 and is journaled therein. At its upper end, the spindle 31 carries a chuck or other suitable gripping member 32 for releasably engaging the lower end 33 of said printing roll shaft. The lower end of the spindle 31 extends freely through a bearing housing 34 (Fig. 3) and is threaded, as at 35. A guard 129 serves to prevent the coating fluid from running from the lower end of the roll shaft down the length of the spindle 31.

A spring pressed clutch member, indicated as 75 a whole by the reference numeral 36, is mounted

on said extended end of the spindle 31 and comprises a disk 37 keyed upon said spindle and a flanged collar or housing 38 adjustably secured on said threaded end 35 by means of a set screw 39. A coiled compression spring 40 is positioned between said collar 38 and the disk 37 and extends into an annular recess 41 in the outer face of said disk.

The housing 34 is provided with opposed socket bearings for receiving the ends, respectively, of a pair of stub shafts 42 and 43, which extend in opposite directions from said housing 34 and are journaled, respectively, in bearings 44 and 45 (Fig. 2) secured to the frame 14. Said shafts 42 and 43 are provided with raised keys 46 and key 47, respectively. A friction faced wheel 48 is mounted on the shaft 42 and held against relative rotation thereon by means of the key 46. A set screw 51, sunk in the face of said wheel 48, permits axial adjustment of the wheel along said shaft 42. A similar friction faced wheel 49 is mounted upon the shaft 43 and movable axially of said shaft into any desired adjusted position while being held from relative rotation by the key 47 and in adjusted position by a set screw 52. The spring 40 of the clutch member 36 normally holds the disk 37 in driving contact with both of the wheels 48 and 49. As is obvious, the relative rotational speed between the wheel 49 and the disk 37, and between the disk 37 and the wheel 48, may be varied by varying the radial distances at which said wheels 49 and 48 are positioned on their respective shafts 47 and 46.

The shaft 42 carries a bevel gear 50 (Fig. 2) that constantly meshes with a bevel gear 53 secured to the lower end of a lead screw 54. Said lead screw 54 is journaled at its lower end in spaced bearings 55 carried by the frame 14 and at its upper end in a bearing 56 mounted from the web 19 of the beam 18. The threaded portion 57 of said lead screw 54 extends substantially the full length of the trough 22.

A carriage 58 (Fig. 4), slidably mounted upon the guide plate 21, carries an apertured boss or sleeve 59 for receiving a rod 60, on the lower end of which is positioned a half nut 61 that is threaded to cooperate with the threaded portion 57 of the lead screw 54. The upper end of the rod 60 is provided with a collar 62 secured thereto and having a cam shaped projection 63 that cooperates with the boss 59 to permit the half nut 61 to be raised from engagement with the screw 57 or to be lowered into engagement therewith.

The carriage 58 has a post 64 extending therefrom which is provided with a socket 65 for receiving a rod 66. A set screw 67 serves to secure one end of said rod 66 in the socket 65. A clamp 68 is mounted on the free end of the rod 66 for adjustably receiving a feed pipe 69. The bracket or clamp 68 may be secured in adjusted position along the rod 66 by means of a thumb screw 70. Likewise, the length of pipe 69 may be adjusted within the clamp 68 by loosening the nut 71 and held in adjusted position by tightening said nut (Fig. 1). A handle 72 is provided upon the clamp 68 to facilitate its manipulation. The carriage 58 carries a splash guard 73 that extends inside of the trough 22 (Fig. 4) to protect the thread 57 of the lead screw from the coating material during the coating operation.

The feed pipe 69 is provided with a discharge nozzle 74 that terminates in slightly spaced re-

lation to the surface of the roll 29 that is being coated. The adjustment already described, including the socket post 64, set screw 67, rod 66, set screw 70, clamp 68 and nut 71, permit the position of the nozzle 14 to be adjusted with respect to the roll 29, both angularly and laterally, and also with respect to the distance of its discharge orifice from the surface of said roll. Ordinarily, it is satisfactory to position the nozzle 14 so that it lies above the center line of the roll 29 and along a radius thereof, but the nozzle 14 may be positioned laterally either behind or in front of the center line of the roll and at an angle to a radius thereof if desired. It should be noted that the nozzle 14 is smoothly tapered so as to provide a solid column of fluid coating composition substantially free from air bubbles. The discharge orifice of the nozzle 14 may be either circular or elongated rectangular in cross section.

The feed connections to the nozzle 14 include a flexible hose or conduit 15 which is supported intermediate its ends in an eye 16 carried by a standard 17. The standard 17 may be supported from a motor base 18. Said hose 15 is connected to an upright pipe 19 which is supported by standards 20. A three way valve 21 (Fig. 1) is inserted in the pipeline 19 for controlling the flow of coating material to the nozzle 14. One of the passages of the three way valve 21 is connected by means of an overflow pipe 22 back to the tank 3. A continuation of the pipe 19 leads to the discharge side of a pump 23. The pipe 19, already referred to, leads from the bottom of the tank 3 to the intake side of said pump 23.

A motor 25, mounted on said base 18, provides the source of power for driving the pump 23 and also for rotating the roll 29 and moving the carriage 58. An electrical conduit 26 leads from said motor 25 to a panel 27 mounted from the standards 20. A switch 28 on said panel 27 controls the operation of the motor 25. The drive shaft 29 of said motor 25 is connected through a coupling 30, to a countershaft 31. The pump shaft 32 is similarly connected by means of a coupling 33 to a countershaft 34. Speed reducing gears within a housing 35 provide a drive connection between the shafts 31 and 34. The shaft 34 also carries on its extended end a gear 36 for meshing with the gear 37 on the extended end 38 of the shaft 10. The sprocket gear 39 on the other end of said shaft 10 is connected by means of a chain 40 to a sprocket gear 41 secured on the end of the stub shaft 42.

It is thus apparent that when the motor 25 is energized, the pump shaft 32 will be driven through the reducing gears connecting the stub shafts 31 and 34. The shaft 10 will also be driven through the gear 36 on the stub shaft 34 and the gear 37 on said shaft 10. Said shaft 10 drives the stub shaft 42 through the sprocket gears 39 and 41 and chain 40. The drive is transmitted from the stub shaft 42 through the friction wheel 43 to the disk 44, which is spring pressed thereagainst. Rotation of said disk 44 effects the driving of the spindle 45 and through the chuck connection 46, the rotation of the roll 29. Obviously, the speed of rotation of said roll 29 can be varied by varying the position of the friction wheel 43 relative to the axis of the disk 44, so that the roll 29 may be driven at the desired substantially constant surface speed irrespective of the roll diameter.

The drive of the disk 44 is transmitted to the lead screw through the friction wheel 48, stub shaft 42 and bevel gears 50 and 51. The speed

of rotation of the lead screw 54 can be varied, as previously explained, by adjusting the position of the friction wheel 48 on the stub shaft 42. Through the cooperation of the half nut 61 and the threaded portion 57 of said lead screw 54, the carriage 58 is caused to move along the guide plate 21 lengthwise of the roll 29 at a speed that is controlled in accordance with the thickness of the roll coating desired. Ordinarily, however, it will be unnecessary to change the speed of the lead screw, since for ordinary thicknesses of coating, it is sufficient to vary the angle of the axis of the roll being coated. After the carriage 58 has reached the extreme lower end of its travel during the feeding operation, the half nut 61 may be raised from cooperation with the lead screw 54 by the operation of the cam shaped collar 62 so as to move the carriage 58 back to the upper end of its travel.

In operation, the roll supporting members are adjusted to the proper inclination by means of the threaded rod 120 and nuts 122. The angle of inclination can be read directly on the quadrant plate 16. The motor is thrown in and the members of the friction clutch adjusted so as to give a predetermined peripheral speed to the roll to be coated. The nozzle 14 is then adjusted so as to direct a solid stream of the coating fluid against the surface of the roll, starting at the extreme upper end thereof. The half nut 61 is released into cooperation with the threads 57 of the lead screw to start the travel of the carriage 58 down along the guide plate 21. After a single passage of the nozzle for the full length of the roll, the nozzle is moved away from the roll to discharge into the trough. The chuck 32 is then released from the end of the roll shaft and the roll manually removed and stood upright on the end that was formerly in the chuck 32.

The coating step is best illustrated in Fig. 6. The coating material is discharged from the nozzle 14 in a solid stream 123, which spreads out rapidly to form a film or layer 124. The force of the stream and gravity cause the layer to extend ahead of the nozzle, as at 125, to form a well defined annular wall 126, which advances at the same rate as the nozzle. The coating does not flood the roll 29 in the sense that it does not run unrestrainedly lengthwise of the roll. A large excess of coating material is, however, discharged onto the roll and this excess flows from the underside of the roll in a stream 127, from behind the advancing wall, and into the trough 22. Thence, the excess flows back into the tank 3 and is strained and recirculated.

The coating material sets so rapidly that there is no drainage of surplus coating material from the roll after it has been removed from the coating machine. In fact, if the roll be allowed to rotate in the machine for a minute or two after the coating step is completed, it may then be supported in horizontal rather than vertical position and no flowing of the coating material will take place. The surface of the coated roll is smooth and glossy and needs no further finishing treatment but is ready for immediate use as soon as the coating composition has completely set.

The coating composition itself does not form a part of the present invention, since it is intended to use a standard coating composition on machines of the type described. The usual printing roll composition is made up largely of gelatin or glue with a suitable softening agent such as glycerine.

In order to maintain a substantially constant

viscosity of fluid coating solution, a thermostatically controlled heating attachment is employed. One suitable type of heating attachment comprises an electrical heating unit contained within a separate compartment, indicated at 105 (Fig. 1), beneath the tank 3. A thermostat 106 of standard construction is inserted in the electrical circuit of the heating unit. A switch 107, suitably mounted upon the panel 87, is inserted in the heating circuit and is connected to the thermostat 106 by wires passing through a conduit 108 and a flexible conduit 109 leading from the thermostat 106 thereto. A thermometer 110 is positioned with its thermo sensitive end directly in the pipe 79 so as to give an exact indication of the temperature of the coating fluid being delivered to the nozzle 74. Preferably, a temperature of about 145° F. is maintained.

In order to eliminate as many variables in the coating operation as possible, it is preferable to maintain a substantially constant peripheral speed of the roll to be coated regardless of its diameter. The rate of travel of the nozzle carrier may also be kept substantially constant for ordinary operation, although it is advantageous to be able to vary the speed of travel of the nozzle under special circumstances, as where an unusually thick or unusually thin coating is desired. As has already been explained, the provision of a variable speed friction drive connection between the driving motor and the roll and between the driving motor and the lead screw makes possible the obtaining of substantially uniform peripheral speeds for different diameters of printing rolls to be coated.

The following table will indicate the manner in which the thickness of coatings may be varied by varying the angular inclination of the roll, while maintaining the surface speed of the rolls substantially constant:

Dia. roller	Roller R. P. M.	Surface speed, inch per minute	Thickness of film			
			30°	25°	20°	15°
			Incline			
4"	23	282	.029"	.035"	.045"	.058"
4½"	20	283	.030"	.035"	.046"	.059"
5"	18	289	.029"	.034"	.045"	.059"

Temperature of coating liquid: 145° F.

Speed of nozzle carrier: 13" per minute.

Viscosity of coating material same for all rollers.

It will be noted from the above table that the thickness of film does not vary more than .001" on the coated rollers, despite the variation in diameters of the rollers of from 4 to 5". The importance of being able to regulate the conditions of operation as closely as the above table indicates and to eliminate the variables heretofore present in coating operations of this type is obvious. It should also be noted that in order to obtain coating films of widely varying thickness, it is very important that the machine be capable of supporting the roll to be coated at widely varying inclinations. Although a difference of only 15° of angular inclination is shown in the above table, the machine is capable of supporting the roll to be coated in any angular position from the horizontal to about a 45° angle from the horizontal. This is an important feature that was not present, to the best of my knowledge, in previous machines for coating printing rolls.

The ability to obtain uniform, relatively thick

coatings in one operation by the use of my machine is especially important in connection with the coating of printer's rollers for use in color work. In that case, a sufficiently thick coating is applied to permit relatively narrow annular sections of coating to be removed at properly spaced intervals along the roll and thus provide separate inking sections, to which may be applied differently colored inks without danger of the inks intermingling in the printing operation. It is preferable in removing the annular sections of coating not to cut completely through the coating but only to a depth of, say, $\frac{1}{16}$ to $\frac{1}{8}$ ". Otherwise, it would be necessary to seal the joint between the coating and the roll base to prevent the seepage of inks between the coating and base. I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. Apparatus for coating printing rolls and the like to a predetermined thickness of coating that may be varied as required, comprising a guiding and supporting member, a driven shaft supporting one end of said member for pivotal movement thereabout, means for adjustably supporting the other end of said member to vary the angular inclination of said member, means carried by said member for rotatably supporting a roll, a trough secured to said member, a coating fluid nozzle, a carriage therefor movably mounted on said member and guided thereby, a receptacle beneath said trough, means connected to said trough and to said nozzle for supplying a coating fluid to said nozzle and means connected to said shaft for rotating said roll and for moving said carriage axially thereof on said guiding and supporting member.

2. Apparatus for coating printing rolls and the like to a predetermined thickness of coating that may be varied as required, comprising a guiding and supporting member, a driven shaft supporting one end of said member for pivotal movement thereabout, means for adjustably supporting the other end of said member to vary the angular inclination of said member, means carried by said member for rotatably supporting a roll, a trough secured to said member, a coating fluid nozzle, a carriage therefor movably mounted on said member and guided thereby, a receptacle beneath said trough, means connected to said receptacle and to said nozzle for supplying a coating fluid to said nozzle and means connected to said shaft and having a variable speed friction drive connection with said roll and with said nozzle carriage for rotating said roll and for moving said carriage axially thereof on said guiding and supporting member.

3. In apparatus for coating printing rolls and the like to a predetermined thickness of coating that may be varied as required, a stationary support, a driven shaft journaled thereon, a roll supporting member supported at one end upon said shaft for pivotal adjustment thereabout, means adjustably supporting the other end of said member at variable heights to vary the angular inclination of said member and roll, roll rotating means carried by said member for releasable connection to an end of said roll and means operatively connecting said driven shaft and said roll rotating means independently of

the angular inclination of said roll supporting member.

4. Apparatus for coating printing rolls and the like to a predetermined thickness of coating that may be varied as required, comprising a guiding and supporting member, a driven shaft supporting one end of said member for pivotal movement thereabout, means for adjustably supporting the other end of said member to vary the angular inclination of said member, means carried by said member for rotatably supporting a roll, a trough secured to said member, a coating fluid nozzle, a carriage therefor movably mounted on said member and guided thereby, a receptacle beneath said trough, means connected to said receptacle and to said nozzle for supplying a coating fluid to said nozzle and means connected to said shaft and having a variable speed friction drive connection with said roll for rotating said roll.

5. In apparatus for coating printing rolls and the like to a predetermined thickness of coating that may be varied as required, a stationary support, a driven shaft journaled thereon, a roll supporting member supported at one end upon said shaft for pivotal adjustment thereabout, means adjustably supporting the other end of said member at variable heights to vary the angular inclination of said member and roll, roll rotating means carried by said member for releasable connection to an end of said roll, a nozzle carriage movable lengthwise of said roll, a nozzle adjustably carried by said carriage for positioning in predetermined spaced relation to the periphery of said roll, means for supplying a coating fluid to said nozzle and means operatively connecting said driven shaft and said roll rotating means independently of the angular inclination of said roll supporting member.

CHARLES F. SMITH. 20
